UNITED STATES PATENT OFFICE.

TATSUKICHI ENOCHTY, OF NEW YORK, N. Y., ASSIGNOR OF ONE-HALF TO SOL KANN,
OF LEONIA, NEW JERSEY.

NON-REFILLABLE BOTTLE.

1,176,281.

Specification of Letters Patent. Patented Mar. 21, 1916.

Application filed August 4, 1915. Serial No. 43,523.

To all whom it may concern:

Be it known that I, TATSUKICHI ENOCHTY, a subject of the Emperor of Japan, residing at New York city, in the county and State of New York, have invented certain new and useful Improvements in Non-Refillable Bottles, of which the following is a specification.

My invention relates to means for preventing unauthorized refilling of receptacles. The term generally applied to this type of devices is non-refillable bottle.

The principal object of the invention is to provide simply constructed means which will effectually prevent the refilling of a receptacle, such as a bottle, after its original contents have been discharged therefrom.

The preferred form in which my invention is embodied is illustrated in the accompanying drawing, in which—

Figure 1 is a vertical sectional view of a portion of a bottle having my invention applied thereto, the bottle being upright; Fig. 2 is a similar view, the bottle being in substantially horizontal position; Fig. 3 is a similar view, the bottle being in a substantially vertical or decanting position; Figs. 4 and 5 are plan views of plates or disks forming part of my invention; Fig. 6 is a perspective view of a spider which I preferably use to retain my invention in place on a bottle neck; and Fig. 7 is a similar view of a movable dome at the discharge end of the device.

Referring to the accompanying drawing by reference characters, 10 denotes the neck of a bottle over which my device is applied. This device includes a substantially conical casing or sleeve 11 which is securely held in position by means of the spider shown in Fig. 6. The spider comprises an annular split ring 12 with arms 13 in the plane of the ring, and fingers 14 substantially at right angles to the plane of the arms 13. The spider embraces the bottle neck below its mouth, the split ring 12 being seated in an annular groove 15, and the arms 13 being seated in parallel vertical grooves 16 all formed in the exterior of the bottle neck, the fingers 14 entering suitably formed notches 17 in the inner face of the sleeve 11, at its thickened portion 11a.

Interposed between the fingers 14 and the bottle neck is a packing gasket 18 which is seated in a suitable groove 18a, this gasket

serving to additionally hold the casing 11 in position. A considerable portion of the sleeve 11 projects upwardly beyond the bottle mouth and forms a housing within which the operative parts of my device are 60 movable.

Placed immediately over the mouth of the bottle is a disk 19 (Fig. 5) having its upper edge beveled to contact with a shoulder 20 formed interiorly of the casing 11 a short 65 distance above the mouth of the bottle. The disk 19 is provided with a number of slots 21 arranged in an annular series, a short distance in from the periphery of the disk.

Movable within the casing 11, above the 70 disk 19, is a second disk 22 (Fig. 4), this disk having an upturned edge 23, and a series of apertures 24 arranged in a circle and fairly closely adjacent the center of the disk which is formed as an upwardly projecting teat 25. The upper face of this disk is provided with a plurality of, preferably three, depressions 26 which form seats for balls 27, superimposed on the disk 22. The teat 25 serves to keep the balls 27 spaced 80 apart. It will be noted that the slots 21 in the disk 19 are out of line with the slots 24 in the disk 22, so that when these disks are in contact the intact portion of one disk will 85 overlie and close the slots in the other disk.

Movable in the upper conical portion of the casing 11 is a dome which is shown in detail in Fig. 7. The dome includes the frusto-conical base portion 28, and the upper cylindrical portion 29. The base is 90 inferiorly hollow and communicates with the series of annular outflow slots 30 formed in the head 29. The lower face of the base 28 is formed with legs or projections 31 designed to contact with the upwardly turned 95 edge 23 of the disk 22. Engaging the upper portion of the outer periphery of the casing 11 is a sleeve 32 which may be of metal or other suitable substance, and is provided with an inner packing gasket 33 which contacts with the cylindrical portion of the casing 11. The casing 11, the disks 19 and 22, the balls 27, and the dome are preferably 100 made of porcelain, although any other suitable material may be employed.

The operation of the invention will be understood from the following description:—Fig. 1 shows the position of the parts when the bottle to which my invention is applied stands upright. It will be there 110

noted that the disk 19 rests immediately over the bottle mouth, the disk 22 rests on the disk 19, the balls 27 rest over the orifices 24, and the dome has descended to such a position 5 that its outlet orifices 30 are below the upper end of the casing 11 and its cylindrical depending teat 34 is a very short distance removed from the upwardly extending teat 25 of the disk 22. It is obvious that when 10 the parts have assumed the position described refilling of the bottle is precluded owing to the fact that the orifices 21 and 24 are sealed. If it be assumed that the bottle is in a substantially horizontal position, the position 15 of Fig. 2, refilling is also prevented. Although the dome has its openings 30 projecting beyond the upper edge of the casing 11 the weight of the balls 27 is sufficient to force the two disks 19 and 22 into contact 20 with the lower disk casing over the bottle mouth. No liquid can be filled into the bottle when the latter is in this position. In the third position assumed by the bottle, that is the inverted position shown in Fig. 25 30, refilling is also prevented, inasmuch as if such refilling were attempted through the openings 30, which are the only accessible openings from the outside of the bottle, the liquid would have to be forced in under pressure, and this would tend to drive the balls in the direction of the bottle neck, the result of which would be that the disks 19 and 22 would be forced inwardly and caused to seat over and close the bottle mouth. When 35 the device is in the position of Fig. 3, the liquid flows out through the orifices 21 and 24, around the balls 27, and out through the outflow openings 30 in the upper part of the dome.

40 What I claim as new and desire to secure by Letters Patent is:—

1. The combination with the neck of a receptacle, of a casing held thereon, a pair of relatively movable orificed disks in said casing, means whereby the orifices in the outermost disks are closed when said receptacle is upright, and a dome freely slideable in said casing and having a contracted upper end adapted to protrude beyond the casing, 45 said upper end being provided with openings through which the contents of said receptacle may issue.
2. The combination with the neck of a receptacle, of a casing held thereon, a disk 50 within said casing and adapted to seat directly on the mouth of said receptacle, said disk having an annular series of orifices adjacent its periphery, a second disk in superposed relation to said first named disk and 55 having a series of orifices adjacent its center and arranged inwardly from its periph-

ery, a dome slideable within said casing and having a contracted upper end adapted to protrude beyond the casing, said upper end being provided with openings through which 65 the contents of said receptacle may issue, and means for closing the orifices in said second named disk.

3. The combination with the neck of a receptacle, of a casing secured thereto, a 70 pair of orificed disks in superposed relation and relatively movable within said casing, the orifices in one disk being out of line with the orifices in the adjacent disk, a dome movable at the outer end of said casing, and 75 balls arranged between said dome and the outermost disk and adapted to close the orifices in the latter.

4. The combination with the neck of a receptacle, of a casing held thereon and projecting upwardly therefrom, a pair of orificed relatively movable disks in said casing, one of said disks being designed to seat directly on the mouth of the bottle, means for limiting the movement of each of said disks 80 within said casing, and a dome slideable within said casing and having a contracted upper end adapted to protrude beyond said casing, said upper end being provided with openings through which the contents of said receptacle 85 may issue.

5. The combination with the neck of a receptacle having an annular groove and a series of vertical grooves therein, of a casing embracing said receptacle neck and having 95 a series of parallel notches therein, means for securing the casing to the receptacle, said means comprising an annulus seated in the groove in the receptacle neck, arms seated in the said parallel vertical grooves and fingers 100 entering the notches in said casing, and means within said casing to prevent refilling of said receptacle.

6. The combination with the neck of a receptacle, of a casing secured thereto, an orificed disk movable toward and away from the receptacle mouth within said casing, a second orificed disk in superposed relation with said first named disk and provided with a central teat, a dome in said casing and having a depending teat in line with said first named teat, and a series of balls interposed between said second named disk and said dome and held in spaced relation by said teats.

In testimony whereof I have affixed my signature in presence of two witnesses.

TATSUKICHI ENOCHTY.
